UNITED STATES PATENT OFFICE.

HERBERT S. JANDUS AND NORMAN VAN HUSEN, OF DETROIT, MICHIGAN, ASSIGNEES
TO THE C. G. SPRING & BUMPER COMPANY, OF DETROIT, MICHIGAN, A CORPORA-
TION OF DELAWARE.

DESIGN FOR A MASK PLATE FOR VEHICLE BUMPERS.

Application filed June 17, 1927. Serial No. 22,482. Term of patent 14 years.

To all whom it may concern:

Be it known that we, HERBERT S. JANDUS and NORMAN VAN HUSEN, citizens of the United States, residing at Detroit, in the county of Wayne and State of Michigan, have invented a new, original, and ornamental Design for Mask Plate for Vehicle Bumpers, of which the following is a specification, reference being had to the accompanying drawing, forming part hereof, wherein—

Fig. 1 represents a front elevation and

Fig. 2 a plan view of a mask plate for vehicle bumpers exhibiting our new design.

The head of the bolt by which the mask plate is clamped to the vehicle bumper is shown in dotted lines.

We claim:

The ornamental design for a mask plate for vehicle bumpers, substantially as shown and described.

HERBERT S. JANDUS.
NORMAN VAN HUSEN.
